US00D497605S1

(12) **United States Design Patent** (10) Patent No.: **US D497,605 S**
(45) Date of Patent: **** Oct. 26, 2004**

(54) **CORDLESS TELEPHONE**

(75) Inventors: **Hartmut Heinrich Esslinger**, Sunnyvale, CA (US); **Howard Geoffrey Nuk**, Sunnyvale, CA (US); **Kevin Christian Coullahan**, Sunnyvale, CA (US); **Jon Christopher Lake**, Sunnyvale, CA (US); **Michael J. Slipy**, Fort Lauderdale, FL (US)

(73) Assignee: **Disney Enterprise, Inc.**, Burbank, CA (US)

(**) Term: **14 Years**

(21) Appl. No.: **29/195,363**

(22) Filed: **Dec. 9, 2003**

Related U.S. Application Data

(63) Continuation of application No. 29/160,074, filed on May 3, 2002, now Pat. No. Des. 487,445.

(51) LOC (7) Cl. **14-03**

(52) U.S. Cl. **D14/147**

(58) Field of Search **D14/137, 138, D14/218, 147-148, 247-249, 401, 144, 455, 456, 341-347, 338-340, 399, 426, 387, 429, 453, 434, 447, 140-142, 430, 149-151, 251-253, 329-330, 240, 241; 379/433.01-433.13, 434, 419, 420.01-420.04, 428.01-428.02, 440, 368-370, 435, 436, 454-455; 320/110-115; 455/550.1-90.3; D13/168; D18/2, 7; 345/168, 169; D21/329, 331, 517**
